UNITED STATES PATENT OFFICE.

DOMINICK NIDEROEST, OF BUFFALO, NEW YORK.

CUFF-BUTTON.

SPECIFICATION forming part of Letters Patent No. 767,826, dated August 16, 1904.

Application filed April 18, 1904. Serial No. 203,739. (No model.)

To all whom it may concern:

Be it known that I, DOMINICK NIDEROEST, a citizen of the United States of America, residing at Buffalo, in the county of Erie and State 5 of New York, have invented certain new and useful Improvements in Cuff-Buttons, of which the following is such a full, clear, and exact description as will enable others skilled in the art to which it appertains to make and use the 10 same, reference being had to the accompanying drawings, forming a part hereof.

The object of this invention is to provide a simple and efficient fastening for cuff and collar buttons, studs, and other articles which 15 will permit the ready insertion or removal of the article without soiling or injuring the linen or other material to which it is applied.

With this object in view I construct one head of the button with a tubular stem carrying a fastening device and construct the other head with a sleeve adapted to engage the tubular stem and be engaged and held by the fastening device.

The invention therefore consists in such an 25 arrangement of parts and in certain novel features of the same as will be hereinafter first fully described and then particularly pointed out in the claims.

In the drawings hereto annexed I have 30 shown the invention applied to a link cuff-button.

In the said drawings, Figure 1 is a side view of the button complete with the parts locked together. Fig. 2 is a longitudinal section of 35 the same. Fig. 3 is a detail view showing the parts of the button in perspective and separated, and Fig. 4 is an enlarged detail section of the end of the stem.

In carrying out the invention I form on or 40 secure to the head A of the button a tubular stem B, which is curved in the form illustrated. The end of this stem is provided with external screw-threads C, which extend to and slightly beyond the end of a longitudinal slot 45 D in the stem. Within the stem is a slidable catch E, consisting of a pin or small rod F, disposed longitudinally within the stem, and a tooth or pawl G, rising from said pin be-

tween the ends thereof and projecting through the slot D. A coiled spring H is fitted within 50 the stem between the head of the button and the catch and serves to normally hold the catch against the outer end of the slot. For convenience in assembling I prefer to form the stem with the slot extending entirely to 55 its end. The spring and the catch may be then successively placed in the stem, after which the end of the stem may be closed by securing a bushing I therein. Within the bean or base J of the button I secure an internally-threaded sleeve K, having an annular flange L on its end, the said flange being formed with a radial notch M, as shown.

The construction and arrangement of the several parts being thus known, the operation will be readily understood. After the tubular stem has been inserted through the buttonholes or openings in the cuff or other article the bean or base is engaged over the end of the same and rotated so that through 70 the action of the screw-threads the notched flange will be brought to and against the catch, the result being that the catch will automatically engage the notch and prevent further rotation of the bean. When it is desired to 75 detach the button, the catch is disengaged by a pressure of the finger and the bean then rotated in the opposite direction to remove the same from the stem.

It will be observed that the notched flange 80 serves as a stop by bearing against the outer surface of the bean to prevent the sleeve dropping too far into the bean, thereby preventing the end of the sleeve marring the bean, and that it also avoids the necessity of forming a part of the lock on the bean. Consequently the invention may be readily applied to buttons now in use. All the parts are enclosed, so that when the button is in use a close inspection is necessary to distinguish it 85 from the ordinary solid-stem buttons.

It will be noticed that one end of the pin portion of the catch fits in the bushing in the end of the tubular stem, while the other end of said pin enters the coiled spring. The ends 95 of the pin are thus guided, so that the catch

will move evenly and wabbling of the same while the device is in use is avoided.

The device is extremely simple in its construction and can be manufactured economically.

Having thus described my invention, what I claim, and desire to secure by Letters Patent, is:-

1. In a button or other article, the combination of a head provided with a tubular stem, a bean or base having a sleeve adapted to engage the stem and provided with a notched flange at its end, and a catch carried by the stem and adapted to engage the said notched flange.

2. The combination of a head provided with a tubular stem, a catch mounted in the said stem and projecting through the side of the same, a spring seated within the stem and holding the catch normally toward the end of the stem, and a bean adapted to engage the

end of the stem and carrying a notched flange adapted to be engaged by the said catch.

3. The combination of a head provided with a tubular stem, said stem having a longitudinal slot, a catch consisting of a pin or rod within the stem and a tooth projecting from said rod through the said longitudinal slot, a spring seated within the stem and bearing on the catch and receiving one end of the pin or rod, a bushing secured in the end of the stem and receiving the opposite end of the pin or rod, and a bean adapted to engage the end of the stem and carrying a notched flange adapted to be engaged by the catch. 30 35

In testimony whereof I have signed this specification in the presence of two subscribing witnesses.

DOMINICK NIDEROEST.
